(57) **CLAIM**

The ornamental design for a stalk for vehicle, as shown and described.

DESCRIPTION

FIG. 1 is a front, left side, top perspective view of a stalk for vehicle showing our new design;

FIG. 2 is a front, right side, top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depicting a boundary around the de-emphasized elements, and the de-emphasized elements within, illustrate portions of the stalk for vehicle that form no part of the claimed design.

1 Claim, 4 Drawing Sheets
